UNITED STATES PATENT OFFICE

RAYMOND A. KLOCK, OF CLOSTER, NEW JERSEY, ASSIGNOR TO GOULD STORAGE BATTERY COMPANY, INC., OF NEW YORK, N. Y., A CORPORATION OF NEW YORK

RADIO APPARATUS

Application filed July 30, 1923. Serial No. 654,565.

My invention relates to radio apparatus and particularly to means for charging the batteries and using the radio set at the same time and to means for readily varying the applied voltages to the detector and amplifying tubes of the set. My invention also includes means for covering the numerous wires and conductors so as to protect them from the action of the battery gases, thus prolonging the lives of the conductors and adding greatly to the value, appearance and convenience of the set.

My invention relates to the arrangement of the various elements of the set and to certain novel connections and circuit arrangements which will be fully described herein-after.

My invention will be better understood by reading the following description taken in connection with the accompanying drawings in which Fig. 1 is a top plan view of a unit for use on direct current; Fig 2 is a side elevation of the unit shown in Fig. 1; Fig. 3 is a top plan view of a unit for use on alternating current; Fig. 4 is a side elevation of the unit shown in Fig. 3; Fig. 5 is a top plan view of a B-battery unit for use on alternating current; Fig. 6 is a side elevation of the unit shown in Fig. 5; Fig. 7 is an end elevation of the unit shown in Figs. 5 and 6; Fig. 8 is a top plan view of a combination A and B-battery unit for use on the alternating current; Fig. 9 is a sectional view through a battery vent cap; Fig. 10 is a diagrammatic circuit arrangement for the unit shown in Figs. 1 and 2; Fig. 11 is a circuit diagram showing the connections for charging an A-battery with two rectifiers; Fig. 12 is a circuit diagram showing the connections for charging an A-battery with one rectifier and B-batteries with two rectifiers, a common transformer being used for both charging outfits, and Fig. 13 shows a B-battery switch in elevation.

Referring to the drawings (Figs. 1, 2 and 10), a container 1, holds an A-battery 2, a switch plate 3 and resistance 4. A meter 5 is located on the switch plate. The container 1 is divided into three compartments A, B and C by walls D and E. The battery 2 is

placed in compartment A; the switch plate 3 in the compartment B and the resistances 4 in the compartment C.

The terminal 6 of the battery 2 is connected by a conductor 7, with one end of the resistances 4, which resistances are connected in parallel. The other end of the resistances 4 are connected with a terminal 8. The positive terminal 9 of the battery 2 is connected with the meter 5 which, in turn, is connected with the terminal 10 on the switch plate 3. The terminal 11 is connected with the terminal 12. A terminal 13 is connected with a terminal 14, and the terminals 15, 16, 17 and 18 are connected at intervals with a resistance 19 as shown in Fig. 10. One end of the resistance 19 is connected to the battery terminal 6 through a conductor 20. A conductor 21, provided with a grip adapted to fit over the terminals or prods 15, 16, 17 and 18, may be connected with either desired one of the prods or terminals 15 to 18. Between the terminals 22 and 23 is connected a condenser 24 one side of which is connected to the receiving set by a wire 25 shown in dotted lines in Fig. 10 and the other end of which is connected to the ground 26.

A switch 27 shown in dotted lines in Fig. 10 connects the terminals 10 and 11 together and also in another position connects the terminals 10 and 13 together. This switch is preferably like that shown and described in the application of William S. Gould and Raymond A. Klock, Serial No. 652,049 filed July 17, 1923, but obviously other forms of switch may be used. When the terminals 10 and 11 are connected together, the unit is properly connected for charging the battery and when the terminals 10 and 13 are connected together the unit is properly connected for operating the receiving set. The power for charging the battery is supplied from the ordinary domestic circuit through the terminals 8 and 12.

Occasions may arise when it is desired to operate the receiving set at the same time the battery 2 is connected to the line. By the provision of the condenser 24 in the circuit as shown in Fig. 10 and by connecting together the terminals 10 and 11 and by trans-

55

65

70

75

80

85

90

95

100

ferring the wire 26' to the terminal 9, the receiving set may be operated while the battery is connected to the line without any objectionable noise from the source of supply. The terminal 9 is provided with a special lug upon which the grip on the wire 26' may be plugged.

Figs. 3 and 4 show a unit comprising a container 28, a battery 29, switch plate 30 and 10 and a rectifier 31. The container 28 is divided into compartments similar to the compartments A, B and C of the container 1. The compartment A contains the battery 29, the compartment B contains the switch plate 30 15 and the compartment C contains the rectifier 31. The prods 32 and 33 are connected to the ends of the primary of a transformer, (not shown). One end of the secondary of the transformer is connected to the prod 34 and 20 the other end of the transformer is connected to one terminal 35 of the rectifier and the other terminal 36 of the rectifier is connected to one terminal 37 of the battery. The other terminal 38 of the battery is connected to the 25 prod 39 so that when the terminals 34 and 39 are connected together the energy which may be supplied from the ordinary domestic circuit to the terminals or prods 32 and 33 passes through the transformer and the rectifier to 30 the battery to charge the same. The switch plate 30 also carries prods 40, 41, 42, 43 and 44. In operation and function the prods 41 to 44, correspond with the prods 147 to 150, shown in Fig. 11, and the prods 34, 39 and 35 40 correspond with the prods 137, 138 and 141, respectively of Fig. 11. Also the prods 32 and 33 correspond with the prods 132 and 133, respectively of Fig. 11 and the prods 45 and 46 correspond with prods 145 and 142, 40 respectively of Fig. 11. The function of these prods will be described in detail in connection with Fig. 11 which illustrates one of the circuit diagrams therefor.

It will be observed that the compartments 45 A, B and C are separated by partitions 28^a and that a similar element 28^b is interposed between the rectifier and the adjacent end of the container or case 28, and it is preferable that these members be formed with vertical 50 flues or channels 28^c. The provision of these members is an important feature for the reason that they provide heat insulating means between the compartments and particularly about the rectifier. In the operation 55 of a rectifier, particularly one of the dry type, considerable heat is evolved and in a unitary structure such as this the heat generated may, unless dissipated, cause excessive evaporation of the electrolyte in the storage battery. By 60 providing these spacing, partition or heat insulating members and especially by forming them with the air flues adequate protection against overheating is avoided. Furthermore the location of the compartment B between the compartments A and C containing 65

the storage battery and rectifier respectively aids in preventing the transfer of heat to the storage battery.

Fig. 5 shows a top plan view of a container carrying three B-batteries 47, 48 and 49, a 70 switch plate 50 and two rectifiers 51 and 52. This container is also provided with three compartments A, B and C. The compartment A carries the battery 47 and the rectifier 51, the compartment B carries the battery 48 and the switch plate 50 and the compartment C carries the battery 49 and the rectifier 52. The switch plate carries prods 53, 54, 55, 56, 57, 58, 59 and 60 and a switch 75 61. The circuit connections for the unit shown in Fig. 5 are shown in Fig. 12 in connection with the circuit connections for an A-battery and a rectifier for charging the same.

Fig. 8 shows a unit comprising a container carrying three B-batteries 62, 63 and 64 and an A-battery 65, a rectifier 66 for the A-battery and two rectifiers 67 and 68 for the B-batteries and a switch plate 69. A complete wiring diagram for the unit shown in Fig. 8 is shown in Fig. 12. The container like the others heretofore described is divided into three compartments A, B and C. The compartment A contains the B-battery 62 and two B-battery rectifiers 67 and 68, the compartment B contains the switch plate 69, A-battery rectifier 66 and A-battery 65. The compartment C contains the B-batteries 63 and 64. The conductors for connecting the parts of the unit may be arranged in 80 runways or grooves in the partitions as illustrated.

The switch plate 69 is provided with a number of prods through which a great variety of circuit connections may be made. The transformer primary 70 is connected to the prods 71 and 72 which may be connected with the domestic lighting circuit to furnish the energy for charging the batteries or operating a receiving set. One end of the secondary 73 is connected to a prod 74 and an intermediate point on the secondary 73 is connected to one element 75 of the rectifier 66 through a conductor 76. The other element 77 of the rectifier is connected to the negative terminal 78 of the battery 65. The positive terminal 79 of the battery 65 is connected to a prod 80 of the switch plate. When the prods 74 and 80 are connected together the battery 65 is connected with a portion of the transformer secondary through the rectifier 66 and is, therefore, charged therethrough. The switch plate is also provided with prods 81, 82 and 83. When the prods 80 and 81 are connected together the rectifier is disconnected from the battery and the battery connected to the prods 82 and 83 which are, in turn, to be connected to the receiving set and which receiving set is, therefore, fed by the battery. The prod 83 is connected to the 100 110 115 120 125 130

negative side of the battery through conductor 84 which may be connected to any desired one of the prods 85, 86, 87 or 88, which are connected at intervals along the resistance 89 so that the voltage between the prods 82 and 83 may be varied by varying the connection on these prods. The resistance 89 is connected to the negative terminal of the battery through conductors 90 and 91, shown 10 in Fig. 12.

One end of the secondary 73 is connected through a wire 92 to contacts 93 and 93' on a switch shown diagrammatically in Fig. 12 and in sectional elevation in Fig. 13. The 15 other end of the secondary 73 is connected with one of the elements 94 of the B-battery rectifier 68. A dissimilar element 95 of the rectifier 67 is connected with the element 94 by a conductor 96. The element 97 of the 20 rectifier 68 is connected to a contact 98 and the element 99 of the rectifier 67 is connected to a contact 100. The positive terminal of the B-battery 64 is connected to terminal 101, the positive terminal of the B-battery 63 is connected to 102 and the positive terminal of the B-battery 62 is connected to the contact 103. The middle point of the battery 64 is connected to terminal 104, the middle point of the battery 63 is 25 connected to 105, and the middle point of the battery 62 is connected to the terminal 106. The negative terminal of the battery 64 is connected to a contact 107 and also to the prod 108. The negative terminal of the battery 63 is connected to the terminals 109, and 110 and the negative terminal of the battery 62 is connected to the terminals 111 and 112. The terminal 113 is connected with the prod 114. The prod 115 is connected to 30 the point 116 on the battery 64, the prod 117 is connected to the point 118 on the battery 64, the prod 119 is connected with the point 120 of the battery 64 and the prod 121 is connected with the point 122 of the battery 64. 35 These connections are for the purpose of varying the voltage on the detector tube.

The switch shown in sectional elevation in Fig. 13 comprises a base 123 into which the 40 contacts 93, 93', 98, 100 to 107, and 109 to 113, inclusive, are embedded. A movable element 124 is arranged above the plate 123 and carries a series of contacts, two of which are shown at 125 and 126. The member 124 together 45 with the contacts carried thereby, is movable for the purpose of making certain connections which will now be described in detail.

When it is desired to charge the B-batteries the member 124 is moved to the left or 50 positioned as viewed in Fig. 13 whereupon the contacts 101, 102 and 103 are connected to the contact 100 and are therethrough connected together; contacts 104 and 105 are connected to the contact 93 and therethrough 55 are connected together; the contacts 107, 109

and 111 are connected to the contact 98 and therethrough are connected together and contacts 106 and 93' are connected together and to contact 93. By this movement of the switch the batteries 62, 63 and 64 are connected in multiple and are connected to the rectifiers 67 and 68 and to the transformer so that the batteries are charged through the rectifiers 67 and 68 from the line which is connected to terminals 71 and 72. It 70 will be noted that, in the embodiment illustrated, each battery is shown as composed of twelve cells so that, assuming that each cell has a potential of approximately two volts, the normal voltage required for charging the batteries if they were merely arranged in multiple or parallel would be approximately twenty-four volts or about four times the voltage required for charging the A-battery 65 which is illustrated as composed of three cells. By having taps to the mid-points of these batteries and having these mid-points, when the batteries are charged, connected to one side of the transformer secondary through contacts 93 and 93' and conductor 92 with the rectifier 67 75 properly connected to the plus poles of the batteries and the rectifier 68 connected in the opposite manner to the minus poles of the batteries, the charging voltage required is cut in half as will be apparent to those skilled in the art. By the arrangement disclosed, the rectifier 67 charges during the half cycles in one direction through the positive halves of batteries 62, 63 and 64, whereas the rectifier 80 90 95 100 105 110 115 120 125 130 68 charges during the opposite half cycles through the negative halves of said B-batteries. An important result is secured by the foregoing arrangement in that both waves or half cycles of the alternating current are utilized for charging the B-batteries, and the voltage used for charging said batteries is approximately double that used for charging the A-battery 65 so that the charging tap to the A-battery is taken from approximately the mid-point of the secondary coil 73. If the charging of the B-batteries was effected while the same were connected merely in multiple without any connection to the mid-points and a single transformer were used for both the A and B-batteries, the charging tap for the A-battery would only include about one quarter of the secondary winding instead of one half and a much less efficient arrangement would be secured.

When it is desired to operate the receiving set the member 124 as viewed in Fig. 13 is moved to the right so that contacts 101 and 110 are connected together, contacts 102 and 112 are connected together and contacts 103 and 113 are connected together and contacts formerly made are broken. This movement of the member 124 has the effect of connecting the batteries 62, 63 and 64 in series and

the full voltage of the three batteries is impressed between the prods 108 and 114. Because of the disconnection of the transformer and rectifiers from the B-batteries by the movement of the switch 124 to the right, it will be apparent that, according to this embodiment of the invention, the B-batteries can not be charged at the same time the receiving set is operated. The main reason for this difference as compared with some of the formerly disclosed embodiments is because of the arrangement whereby the B-batteries are charged in multiple and discharged in series, it being obvious that the full series voltage would not be available for the receiving set during the parallel or multiple connection of the batteries for charging purposes. By suitably connecting the prods 108 and 114 to the receiving set, the B-battery voltage is applied thereto. The prods 115, 117, 119 and 121 are connected at intermediate points on the battery 64 for the purpose of providing convenient fractional voltages, particularly useful on the detector tube of the receiving set. The voltage between the various prods 115, 117, 119, 121 is approximately two volts.

In the arrangement shown in Fig. 12, the terminals 71, 72, 74, 80 to 83, 85 to 88 and 108, 114, 115, 117, 119 and 121, are placed upon the switch plate 69. This switch plate also carries the switch shown in Fig. 13.

The prods 82, 83, 108, 114, 115, 117, 119, 121, may be placed on a switch plate, such as that shown in my application Serial No. 649,461, recessed in the front of the container.

Fig. 11 shows a wiring diagram of two rectifiers connected for charging an A-battery. This arrangement comprises a battery 127, rectifiers 128 and 129, a transformer having a primary 130 and a secondary 131. The primary of the transformer is connected to two terminals 132 and 133, which may be connected to the domestic lighting circuit. One end of the secondary 131 is connected to one element 134 of the rectifier 129 and the other end of the secondary is connected to a corresponding element 135 of the rectifier 128. The other elements 136 of the rectifiers are connected together and connected to a terminal 137. The terminal 138 is connected to the positive side 139 of the battery. A conductor 140 connects the negative terminal of the battery to the middle point of the secondary 131 of the transformer. The terminals 141 and 142 are placed upon the switch plate carrying the other terminals and these two terminals are connected together by a conductor 143. A switch is furnished with the apparatus for connecting terminals 137 and 138 together to charge the battery and for connecting terminals 138 and 141 together for operating the receiving set. A choke coil 144 is connected at one end with the con-

ductor 140 and at the other end with the terminal 145. A resistance 146 is connected to the negative side of the battery and terminals 147, 148, 149 and 150 are connected at intervals to the resistance 146. A conductor 151 is provided with a grip so that it may be placed upon any one of the terminals 147 to 150 to vary the voltage on the filaments of the tubes. Each terminal of the battery 127 is so designed that a grip may be plugged thereon so that the required voltages may easily be secured for operating tubes designed for various fractional voltages. The connections therefor are shown in dotted lines in Fig. 11. By this arrangement one and one-half to two volts may be secured between the wire 151 and the wire 152 and three to four volts between the wire 151 and the wire 153. The conductor 151 leads to the receiving set.

By the arrangement shown in Fig. 11, both peaks of the alternating current waves are utilized in charging the battery 127 and, by the provision of the choke coil 144 in the circuit, as shown, the receiving set may be operated while the battery is connected to the line without any objectionable noise. When it is desired to operate the receiving set and, at the same time connect the battery to the line, the terminals 137 and 138 are connected together and the wire 154, leading to the receiving set is plugged onto the prod 145 and any noise which might otherwise be detected in the set is effectively eliminated.

I have discovered that it is not necessary to provide a choke coil for noiseless reception while the battery is connected to the line when the signals are coming in at full strength, but when the signals are weak and maximum regeneration is required it is necessary to use the choke coil for noiseless reception.

I have discovered also that when the device shown is used while the battery is connected to the line the energy for operating the receiving set is supplied direct from the line and the battery is not charged substantially during this period. The battery acts to smooth out the impulses and, therefore, plays an important part in the operation.

In the arrangement shown in Fig. 10 the condenser is necessary at all times when the set is being used with the battery on the line. In both alternating current and direct current the provision of means whereby the set may be used while the battery is connected on the line is a guarantee against failure of the set during a concert on account of failure of battery. What are known as "connector cells" may be substituted in my combination and a battery dispensed with completely and noiseless operation secured.

I believe that the excellent results secured by the combination above described is due largely to the combination of battery, choke coil and an electrolytic rectifier and I prefer

to use a rectifier in which the elements are composed of tantalum and lead.

Fig. 9 shows a section of a battery vent and cap. The threaded portion 155 of the cap is 5 tapered so that upon unscrewing the cap a few turns, the gases from the battery during the charging operation may freely escape without completely removing the cap from the battery. The portion 156 of the vent is 10 also tapered to correspond with the taper on the portion 155 so that when the cap is screwed down tight it prevents leakage of the electrolyte from the battery. The cap is provided with the usual vent opening so that 15 the normal gases discharged from the battery may pass out through the vent in the ordinary way.

From the foregoing, it will be evident that my invention has many advantages, among 20 which may be mentioned that all of the battery elements and switching apparatus are assembled in one unit and terminals provided at convenient points for varying the connections to the batteries so as to vary the 25 voltage upon the various elements of the receiving set; the various contacts and conductors are either made of metal which is inert to the action of battery gases or they are coated or encased in material which is inert 30 to the battery gases so that the objectionable corrosion present in the battery arrangements as heretofore constructed is entirely eliminated with the result that the appearance of the outfit is much improved and also the connections are much more effective and the 35 objection from noises due to defective connections is entirely eliminated; means, such as a blocking condenser in the direct current set-up and the choke coil in the alternating current set-up, are provided whereby the receiving set may be used while the battery is 40 connected to the line thus avoiding the objection of having the battery become discharged during a concert or other period of entertainment; the spaces between the various elements 45 are utilized for the wiring, and sealing compound is placed over and around the conductors so as to securely hold them in place and, at the same time, to completely cover and 50 encase them in a material which protects them from the action of the battery gases. This arrangement adds greatly to the appearance of the battery unit and, at the same time, prolongs the life of the conductors by 55 protecting them.

Many other advantages will be apparent to those skilled in the art.

Many slight changes may be made in many of the details without departing from the 60 spirit of my invention.

I claim:

1. In radio apparatus, the combination of a container, a plurality of batteries in said 65 container, each of said batteries comprising an even number of cells, two rectifiers in said

7 container for charging said batteries, conductors for connecting said batteries and rectifiers together, certain of said conductors extending to the mid-points of the batteries and a movable switching means which in one position connects the batteries in series and disconnects the rectifiers therefrom and in another position connects the proper pole of one rectifier with all of the positive poles of the batteries, the opposite pole of the other rectifier with all the negative poles of the batteries, the mid-points of the batteries and the other poles of the rectifiers being adapted for connection with an appropriate source of alternating current.

2. In radio apparatus, a plurality of storage batteries, each of said batteries having an even number of cells, a suitable source of alternating current for charging said batteries, two rectifiers for suitably modifying the current delivered to said batteries, conductors for connecting said batteries to the rectifiers and source of alternating current, certain of said conductors being connected to the mid-points of the batteries, and a manually operated switching device which in one position connects the proper pole of one rectifier with all the positive poles of the batteries, the opposite pole of the other rectifier with all the negative poles of the batteries, the mid-points of the batteries and the other poles of the rectifiers to the source of alternating current and in another position disconnects the rectifiers and source of alternating current from the batteries and connects said batteries in series.

3. In radio apparatus, a plurality of storage batteries, each of said batteries comprising an even number of cells, two rectifiers for charging said batteries, a single transformer for supplying alternating current of the desired voltage to said rectifiers, conductors for suitably connecting the batteries, rectifiers and transformer together, certain of said conductors extending to mid-positions with respect to the cells of the batteries and manually operated switching means for either connecting the batteries in series and disconnecting the rectifiers and transformer therefrom when it is desired to use said batteries or for connecting the proper terminal of one rectifier to all the positive terminals of the batteries, the opposite terminal of the other rectifier to all the negative terminals of the batteries, and the mid-points of the batteries and the other terminals of the rectifiers to the transformer for charging said batteries.

4. In an electrical power apparatus, the combination of a single casing, a storage battery therein, a rectifier within the casing spaced from the storage battery, terminal means for making connections with outside circuits and between the storage battery and rectifier, and means for dissipating the heat 130

generated during the operation of the rectifier whereby the heat will be prevented from affecting the storage battery, said means comprising ventilated members disposed respectively against the storage battery and rectifier and acting as heat insulators.

RAYMOND A. KLOCK.
